UNITED STATES PATENT OFFICE.

VALENTINE JOHN NIELE, OF PITTSBURGH, PENNSYLVANIA.

EAVES-TUBE-STRAINER FASTENER.

Application filed May 22, 1924. Serial No. 715,163.

To all whom it may concern:

Be it known that I, VALENTINE JOHN NIELE, a citizen of the United States, and resident of Pittsburgh, in the county of Allegheny and State of Pennsylvania, have invented certain new and useful Improvements in EavesTube-Strainer Fasteners, of which the following is a specification.

My invention is an improvement in devices for holding a strainer against displacement from position at the upper end of a roof leader or like drain tube, and it consists in the combinations, constructions and arrangements herein described and claimed.

An object of the invention is to provide a simple and reliable device for holding the strainer against displacement from a desirable position at the upper end of a roof leader or like drain tube without interfering with the flow of water into and down the drain tube.

A further object is to provide a fastener of the character described which comprises but relatively few parts, can be manufactured at a relatively low cost and is thoroughly practical commercially.

Other objects and advantages will be apparent from the following description, considered in conjunction with the accompanying drawings, in which—

Figure 1 is a perspective view showing a fastener embodying the invention in position to hold a strainer in place at the upper end of a roof leader, only fragmentary portions of the gutter and drain tube being shown,

Figure 2 is a vertical section through the upper end portion of the drain tube and adjacent portion of the gutter, the strainer and fastener being shown in side elevation, and

Figure 3 is a perspective view of a securing clip which is comprised in the fastener.

Strainers for roof leaders and other like vertically disposed drain tubes ordinarily are held in place by depending tangs or spring fingers which depend in the drain tube below the level of the upper end of the latter. When strainers are held in a desirable position at the upper end of roof leaders and like drain tubes by means of such depending fingers or tangs, the impact of a mass of leaves or like foreign matter against the sides of the strainers is likely to dislodge the strainers from the desirable position and moreover the depending fingers or

tangs tend to interfere with the passage of water into the upper end of the drain tube.

The objectionable features of means for holding strainers in place at the upper ends of roof leaders prior to my invention, of which I am aware, are obviated when a strainer for a roof leader or like drain tube is held in place at the upper end of the drain tube by a fastener formed in accordance with the present invention, as will presently appear.

In Figures 1 and 2, the numeral 1 designates a portion of the bottom of a gutter for a roof. A vertically disposed drain pipe or leader 2 is provided and overlaps a short tubular boss or depending extension 3 which depends from an opening 4 in the bottom of the gutter and may be integral with the latter. A downwardly facing shoulder 5 thus is provided within the drain tube at a slight distance below the level of the bottom of the gutter.

The construction described so far is ordinary and forms no part of the present invention, except in so far as it cooperates with the parts which will now be described.

A strainer 6 having a central opening 7 and made of a network of wires or other foraminous material rests upon the bottom of the gutter in overlying relation to the open upper end of the drain pipe. The strainer 6 is shown as being convexo-concave and as being circular in horizontal sectional contour but obviously may be of any other desirable and suitable shape and configuration. In carrying out the invention, I make use of a length of wire made of material possessing considerable inherent resiliency. The length of wire is bent intermediate its length until doubled and the two members thus produced are twisted together from their juncture for the greater part of their length to provide a substantially straight stem 8. The remaining portions of the two members are bent to provide spring loops at one end of the stem, such as that indicated at 9 and the extreme end portions of the two members are bent to extend oppositely in a general outward and rearward direction, thus providing substantially straight spring engaging fingers as indicated at 10 and 11 respectively.

The length of the spring fingers 10 and 11 is such that the normal straight line distance between the ends of the spring fingers

is greater than the inner diameter of the drain tube 2. It also is to be observed that a straight line extending from the end of one of the spring fingers to the end of the other spring finger lies in a plane intersecting the stem 8 at right angles and at a point inwardly from the junctures of the spring fingers with the stem.

- Therefore, the end of the stem 8 which is provided with the spring fingers may be inserted in the drain tube at the open upper end thereof, the ends of the spring fingers being forced toward each other to permit movement of the inserted end portion of the stem along the drain tube. The ends of the spring fingers of course will slide in contact with the inner wall of the depending tubular extension 3 and as soon as these ends have traversed the depending tubular extension 3, the inherent resiliency of the spring loops which connect the spring fingers to the stems will function to force the ends of the spring fingers away from each other into contact with the inner wall of the drain tube below the lower end of the tubular member 3. Retrograde movement of the stem 8 in the drain tube then will be prevented because of the positive engagement with the ends of the spring fingers with the shoulder 5, the latter of course being the lower end wall of the tubular member 3. The strainer 6 now is slipped over the upper end of the stem 8 and rests upon the bottom of the gutter in position to cover the open upper end of the drain tube, as illustrated in Figures 1 and 2. A spring locking clip 12 which is best seen in Figure 3 now is placed in engagement with the stem 8 in position to engage with the upper side of the strainer 6. The latter thus is clamped down on the bottom of the gutter and is held against any appreciable vertical or lateral movement in respect to the bottom of the gutter and at the same time, the stem 8 is held against further axial movement downward in the drain tube. The locking clip 12 is formed of a length of spring wire bent intermediate its ends to provide a spring loop 13, the ends of the spring wire being bent to diverge apart for part of their length as indicated at 14 and 15 respectively and to extend in a plane which intersects the plane of the spring loop 13 substantially at right angles, the ends of the spring wire then being inclined toward each other and each being provided at its extremity with a coil as indicated at 16 for one of the ends of the spring wire and at 17 for the other end of the spring wire. The coils 16 and 17 are positioned close to each other but out of alignment. The spring connecting loop 13 is slipped over the upper end of the stem 8 against the strainer 6. One of the spring arms of the locking clip then is swung against the action of the spring connecting

loop 13 toward the stem 8 and the securing coil at the inner end of that spring arm is engaged with the stem. The other spring arm of the locking clip then is swung inwardly toward the stem and the engaging coil at its free end also is engaged with the stem. The spring arms of the locking clip thus will be placed under tension which prevents the coils 16 and 17 at the extremities of the spring arms from disengaging the stem 8, these coils being in engagement with the corrugations which are provided by twisting the members of which the stem is composed together. The locking clip will be held against movement along the stem 80 and in engagement with the strainer 6.

From the foregoing description of the various parts of the device, the operation thereof may be readily understood. The stem 8 will be positively held against retrograde movement from the position in respect to the drain tube illustrated in Figures 1 and 2. The strainer will also be held against displacement from the position illustrated in Figs. 1 and 2 because of the pressure applied thereagainst when leaves or other debris lodge against the strainer and the water from the roof then rushes quickly against the matter which has lodged on or against the strainer. It also is to be observed that the use of my improved fastener for holding the strainer in position does not in any way interfere with the flow of water from the gutter into and through the drain tube.

Obviously, my invention is susceptible of embodiment in forms other than that illustrated in the accompanying drawing and I therefore consider as my own all such modifications and adaptations of the form of the device herein described as fairly fall within the scope of the appended claims.

I claim:

1. A fastener of the character described comprising a stem, a pair of spring fingers, spring means connecting said spring fingers to one end of the stem so that the spring fingers extend outwardly and rearwardly in respect to the adjacent end of the stem, said stem being adapted to be inserted in a drain tube to position the spring fingers in frictional engagement at their ends with the inner wall of the drain tube, and means engageable with said stem for holding a strainer on said stem against the adjacent end of the drain tube.
2. In combination with a drain tube having an inwardly facing shoulder adjacent to the open end thereof and a strainer adapted to cover the open end of the drain tube, said strainer having a central opening, a fastener comprising a stem adapted to extend through the central opening of the strainer into the drain tube and having a pair of oppositely and rearwardly extending spring-

- pressed fingers in contact with the inner wall of the drain tube for engaging with said shoulder to hold the stem against retrograde movement, and means engageable 5 with the outer end portion of said stem for holding said spring fingers in engagement with said shoulder and for holding said strainer against displacement from position to cover the open end of the drain tube.
- 10 3. In a fastener of the character described, a stem formed of a length of wire bent intermediate its ends, the end portions thus provided being twisted together for the greater part of their length, said end portions then being bent to provide spring loops at one end of the stem and to provide outwardly and rearwardly extending retaining fingers.
- 15 4. In a fastener of the character described,
- a stem formed of a length of wire bent intermediate its ends, the end portions thus provided being twisted together for the greater part of their length, said end portions then being bent to provide spring loops at one end of the stem and to provide outwardly and rearwardly extending fingers, 20 and a spring locking clip made of a length of wire bent intermediate its ends to provide a spring loop and a pair of spring arms, said spring arms diverging for the greater 25 part of their length and then being bent toward each other and provided with securing coils at their extremities, said spring loop being adapted to be slipped over an end of said stem and said securing coils being adapted to be engaged with said stem, 30 as and for the purpose described.

VALENTINE JOHN NIELE.
